UNITED STATES PATENT OFFICE.

ABRAHAM B. SCHOPF, OF PHILADELPHIA, PENNSYLVANIA, ASSIGNOR TO BARRY CHOCOLATE CO., INC., OF PHILADELPHIA, PENNSYLVANIA, A CORPORATION OF NEW JERSEY.

CANDY-PACKAGE.

No. 906,941.

Specification of Letters Patent.

Patented Dec. 15, 1908.

Application filed July 22, 1907. Serial No. 384,846.

To all whom it may concern:

Be it known that I, ABRAHAM B. SCHOPF, a citizen of the United States, residing in the city and county of Philadelphia, State of Pennsylvania, have invented a new and useful Candy-Package, of which the following is a specification.

My invention consists of a package for candy or other material if so desired, the same consisting of a box having lids on the top or bottom portions of the body thereof, both primarily separate from said body, one of said lids subsequently constituting the fixed bottom of the box, means being employed for causing the latter named lid to adhere firmly to the body, so as to be practically unremovable and produce an air tight joint between the parts, provision being also made for retaining the candy in compact form within the box and resiliently supporting the same, so as to prevent breakage of the candy, the package also presenting an attractive and marketable appearance, the means employed being hereinafter described, 25 and the novel features pointed out in the claims.

Figures 1 and 2 represent perspective views of the top and bottom, both in open condition, of a candy package embodying my invention. Fig. 3 represents a transverse section thereof, of the box in closed condition.

Similar letters of reference indicate corresponding parts in the figures.

Referring to the drawings: A designates a box constructed of the body B, a plurality of lids C, D, both of which are primarily separate from said body, the lid D subsequently constituting the bottom of the box, the latter, in the present case, being intended for candy. The box is lined with paraffin or wax paper E, and the candy placed thereinto and bound by the ribbons or cords F, thus keeping the pieces of candy more compactly within the box.

G designates a cushion, which is placed on the bottom of the box and provides a resili- 50 ent support for the candy superimposed thereon, thus preventing mashing or fracture of the candy.

H designates a strip or piece of paste-board or other suitable material, which is placed on the bottom of the box and adapted to snugly and tightly engage opposite sides of the body 55 of the box, so as to distend said sides and

cause them to contact closely with the sides of the bottom lid D.

In putting up the goods, the lid C is fitted on the body B, and the latter is overturned, so that said lid is on the bottom of the box, 60 the other lid D having been removed said lid C though loose on the body forming in the present position a bottom closure for the same.

The ribbons F are united at their ends and placed on the bottom of the box and up the sides thereof, and the lining E applied. The candy is now packed into the box within the lining, after which the ends of the latter are folded over the top of the candy and the ribbons brought together and tied. The strip H is now placed on the top of the folded lining, so as to press against the side walls of the body B and force them out to normal condition for overcoming any collapsion or 75 shrinking. The cushion G is now placed in position, and the lid D applied and gummed to the body, whereby as the walls of the body are pressed against the sides of said lid, the adhesive material employed causes said lid 80 D to be firmly connected with the body and producing practically an air-tight joint for said members. The box is now overturned, when the lid D becomes the fixed bottom of the box, while the lid C is loose on top and so 85 being removable for access to the contents of the box.

While I specified certain means for carrying out my improvements, I do not wish to be limited exactly to the same, but desire to 90 make such changes as may come within the scope of the novelty involved.

Having thus described my invention, what I claim as new and desire to secure by Letters Patent, is:—

1. A package of the character stated composed of a body, a lining therefor, the material to be packed being adapted to be contained within said lining, a distending strip in said body over said lining, and a binder extending around the bottom, sides and top of said lining and united at its ends.

2. In a package of the character stated, a box composed of a body, a plurality of lids both primarily separated from the body, one of which subsequently constitutes the bottom of the box, a lining for said box independent of the box and its lids, and a distending strip independent of the box and its lids and disposed on the bottom of the box 110

and tightly engaging opposite sides of the body thereof to distend the same and to cause them to closely contact with the sides of the bottom lid.

- 5 3. In a package of the character stated, a box composed of a body, a plurality of lids both primarily separated from the body, one of which subsequently constitutes the bottom of the box, a lining for said box independent of the box and its lids, a cushion supported on the bottom of the box and consti-

tuting a resilient support for the candy and a distending strip independent of the box and its lids and disposed on the bottom of the box and tightly engaging opposite sides of the 15 body thereof to distend the same and to cause them to closely contact with the sides of the bottom lid.
